BOAT LIFT

Ernest D. Le May, Birmingham, Ala., and Eugene K. White, Owensboro, Ky.

Application September 20, 1947, Serial No. 775,352

1 Claim. (Cl. 254—50)

1

Our present invention relates to boat lifts, and more particularly to lifts for small boats and has for an object the provision of an inexpensive light weight boat lift embodying a supporting frame disposed to rest on the ground beneath the water line, and a vertically movable boat frame disposed over the supporting frame, together with cranks or links for raising and lowering the boat frame with respect to the supporting frame.

Another object of our invention is to provide a boat lift of the character described embodying an elongated operating handle for the boat frame elevating mechanism whereby the same may be operated from the boat after the same is positioned over the boat frame, or may be operated from a position alongside the boat, in either case without the operator having to enter the water.

A further object of our invention is to provide a boat lift of the character designated in which one end of the boat frame is pivoted to one end of the supporting frame, and in which a U-shaped elongated operating handle is pivoted to the other end of the supporting frame and carries at its lower end a transverse roller disposed beneath the free or non-pivoted end of the boat frame, whereby the same may be raised or lowered upon movement of the handle.

A still further object of our invention is to provide a boat lift in which a crank is mounted in each end of the supporting frame and pivotally connected to the underside of the boat frame, together with an elongated handle for operating one of the cranks, thus to raise both ends of the boat frame substantially the same amount, thereby providing a structure in which a boat may be wholly floated into position over the device and raised from or lowered into the water by a simple movement of the handle.

Apparatus embodying the features of our invention is illustrated in the accompanying drawings forming a part of this application in which:

Fig. 1 is a side view of our improved boat lift showing a boat in position thereon;

Fig. 2 is a plan view of the device with the boat removed;

Fig. 3 is a rear elevational view of the same;

Fig. 4 is a detail view of one of the adjustable mud sills;

Fig. 5 is a sectional view taken generally along line V—V of Fig. 1;

Fig. 6 is a view similar to Fig. 1 and showing a slightly modified form of our invention;

Fig. 7 is a plan view of the device shown in Fig. 6;

Fig. 8 is a rear elevational view of the modification shown in Figs. 6 and 7;

Fig. 9 is a view similar to Fig. 1 and showing a still further modified form of our boat lift;

Fig. 10 is a plan view of Fig. 9; and

Fig. 11 is a rear elevational view of the device shown in Figs. 9 and 10.

Referring now to the drawings for a better understanding of our invention, and more particularly to Figs. 1 to 5 inclusive thereof, our im-

2

proved boat lift comprises a supporting frame indicated generally by the numeral 10. The supporting frame is formed of longitudinal members 11 and front and rear cross members 12. The entire device is supported on vertically and angularly adjustable mud sills 13 placed at each corner of the supporting frame. As seen more clearly in Fig. 4, each of the mud sills comprises tubular members 14 carrying at their lower end mud shoes 16. The tubular portion 14 is provided with a plurality of holes 16a, the member 14 being telescopically received in a short section of tubing 17, and connected thereto by means of a pin 18. Welded to a side of the short section 17 is a projecting pin or tube 19, the outer end of which is telescopically received within a socket 21, welded to the longitudinal members 11 at the corners of the frame. The sockets 21 are provided with a plurality of holes 22 and a pin 23 passes through these holes and through the member 19 whereby the entire mud sill may be rotated in the sockets 21, thus providing for angular adjustment of the sills. Vertical adjustment is made by means of the pin 18 and holes 16.

The boat frame of our improved device, indicated generally by the numeral 24, comprises a pair of longitudinal members 26 and 27 which may conveniently be light weight channels. Extending across and joined to the members 26 and 27 are fore and aft boat cradles 28 and 29, respectively. The cradle 29 may be secured to the members 26 and 27 by means of screws 31 and the forward cradle 28 is adjustable fore and aft on the longitudinal members 26 and 27 by means of depending brackets 32 and nuts and bolts 33. See Fig. 5. The forward cradle may, therefore, be moved axially along the members 26 and 27 to accommodate boats of different lengths.

The forward end of the boat frame 24 is pivotally mounted on a transverse rod 34 mounted at each end on brackets 36 and 37, welded to the supporting frame members 11. Collars 38 serve to center the boat frame with respect to the supporting frame. At the rear end of the supporting frame are a pair of upwardly directed brackets 39 and 41, supported from the members 11 by means of gusset plates 42 and 43. Pivotally mounted as at 44 and 46 on the brackets 39 and 41 are the ends of the legs of an elongated U-shaped operating handle 47. The lower ends 47a and 47b of the legs project past the pivot points 44 and 46 and are provided with rearwardly extending plates 48 and 49. Mounted on a pin 51 carried by the plates 48 and 49 is a roller 52 upon which the rear ends of the members 26 and 27 rest. The roller 52 thus passes beneath the boat frame 24 and supports the free end thereof.

From the foregoing, the method of constructing and using the form of our invention shown in Figs. 1 to 5, inclusive, will be readily understood. The supporting frame may be placed on a sloping bottom at the edge of a lake or other body of

water to lie with its aft end submerged beneath the water line, indicated generally by the letter W in Fig. 1. With the handle 47 in the raised position as shown in the full lines of Fig. 1, a boat B may be floated between the legs of the operating handle to overlie the rear cradle 29 and with its prow angularly disposed with respect to the longitudinal axis of the boat lift, whereupon the prow of the boat may be manually lifted onto the cradle 28. With the boat thus positioned, the operator, standing either in the boat or on a suitable platform alongside the boat lift, grasps the upper end of the U-shaped handle 47 and pulls the same downwardly to the dotted line position shown in Fig. 1. This causes the roller 52 to move upwardly as indicated, the handle pivoting about the points 44 and 46 thus to raise the rear end of the boat frame 24 and the boat clear of the water. The prow of the boat, being pivoted on the shaft 34 which is disposed forwardly of the forward cradle 28, is raised further out of the water, the boat frame being substantially horizontal when the handle is in the lower position. The boat B is thus raised out of the water and held on the boat frame by a simple downward movement of handle 47. Conversely, when it is desired to lower the boat into the water, the handle 47 is raised upwardly, lowering the rear end of the boat, and, by lifting the prow of the boat out of its cradle 28, the boat is again water borne and may be floated from between the legs of the U-shaped handle 47.

Referring now more particularly to Figs. 6, 7, and 8, we show a slightly modified form of the boat lift shown in Figs. 1 to 5 inclusive. In this modification, a pair of cams 53 and 54 are welded as at 56 and 57 to a cross rod 58, operatively connected at its ends to a U-shaped handle 59. The cross rod 58 is supported in suitable bearing brackets 61 and 62 carried by the longitudinal members 11 of the supporting frame 10. The front end of the boat frame is pivotally mounted on a rod in the same manner as that already described in connection with Figs. 1 to 5 inclusive.

The cams 53 and 54 are disposed to engage the underside of the members 26 and 27 so that when the handle 59 is moved to the dotted position shown in Fig. 6 the boat frame 24 is raised as already explained.

Referring now to Figs. 9, 10, and 11, we show a further modification of our boat lift in which the supporting frame 10 is adapted to be disposed wholly beneath the water line W and in which the boat frame when in lowered position also lies beneath the water line, thereby making it possible to float the boat into position to be raised.

In this modification, we provide fore and aft crank arms 64 and 66, respectively, mounted in suitable bearing brackets 67 and 68 carried by the supporting frame 10. The transverse portions 69 and 71 of the crank are pivotally connected by means of suitable bearings 72 and 73 to the underside of the longitudinal members 74 and 76 forming the main members of the boat frame. The fore and aft cradles 28 and 29 cross connect the members 74 and 76 and act as transverse braces therefor. The crank 66 is provided at one side with an elongated operating handle 77, so positioned that when the boat frame is in its lower position the handle is substantially vertical.

Disposed across the members 11 of the supporting frame 10 are a pair of stop members 78 and 79 which are adapted to limit the downward movement of the crank arms 64 and 66.

In the operation of this modification, the boat is floated into position above the cradles 28 and 29 and the handle 77 is brought downwardly. The frame members 74 and 76 of the boat frame act as links between the cranks 64 and 66 so that the motion of crank 66 is transmitted to crank 64 to cause upward pivotal movement to the latter crank. The stops 78 and 79 prevent the arms from reaching dead center when the boat frame is in the lower position thereby making it possible to raise the boat frame upwardly responsive to upward movement of crank 66.

If desired, a pin 81 may be secured to a side of the crank 64 thus to act as a stop for the end of handle 77 when the same is in down position shown in dotted line, Fig. 9, thereby to make the handle accessible for upward movement. It also will be noted in connection with the modification shown in Figs. 9 to 11 that the stop 81 is so positioned that the cranks 64 and 66 travel past vertical center so that the weight of the boat and the boat frame tend to hold the boat in the raised position.

Referring again to Fig. 7, it will be apparent that stops 82, similar to the stop 81, may be provided in this modification to prevent the handle 59 from traveling beneath the water and that these stops may be so positioned that the load supporting point of the cams 53 and 54 when in the raised position are past the pivot point on which they are supported, thereby preventing the handle from rotating upwardly responsive to the weight of the boat.

From the foregoing, it will be apparent that we have devised an improved boat lift which is economical of manufacture and simple of operation. In actual practice, we have found that a boat lift made in accordance with our invention is satisfactory in every way.

While we have shown our invention in several forms, it will be obvious to those skilled in the art that it is not so limited, but is susceptible of various other changes and modifications, without departing from the spirit thereof, and we desire, therefore, that only such limitations shall be placed thereupon as are specifically set forth in the appended claim.

What we claim is:

In a boat lift, a supporting frame, a boat frame pivotally mounted at one end to the supporting frame, a U-shaped handle of a width to straddle a boat on said boat frame and of a length to extend past an end of a boat on said boat frame and having its legs pivoted to the supporting frame adjacent the free end of the boat frame, the ends of the legs projecting past the pivot points thereof, and a roller carried in the projecting ends of the legs and supporting the free end of the boat frame.
